UNITED STATES PATENT OFFICE.

GEORGE E. SMITH, OF NEW YORK, N. Y.

ANTI-EXTINGUISHING ATTACHMENT FOR GAS-BURNERS.

SPECIFICATION forming part of Letters Patent No. 243,167, dated June 21, 1881.

Application filed March 1, 1881. (No model.)

To all whom it may concern:

Be it known that I, GEORGE E. SMITH, of the city, county, and State of New York, have invented a new and Improved Anti-Extinguishing Attachment for Gas-Burners, of which the following is a full, clear, and exact description.

Figure 1 is a sectional elevation of my improvement shown as applied to a gas-burner. 10 Fig. 2 is a sectional plan view of the same, taken through the line *x x*, Fig. 1.

Similar letters of reference indicate corresponding parts.

The object of this invention is to prevent gas-lights from being accidentally extinguished.

The invention consists of a conical-topped box, having a central diaphragm, apertures being made very near the middle of the box and the diaphragm to permit the box to be mounted 20 upon a gas-burner. In use the cone of the box stands just below the tip of the gas-burner. At the base of the gas-burner a small aperture is made, through which gas constantly escapes when the gas is turned on for use. 25 When the gas is lighted at the burner in the usual manner the escaping gas at the pin-hole also ignites and continues to burn. Should the gas at the burner become extinguished by accident or from being blown out, the flame 30 from the pin-hole will immediately ignite the escaping gas from the burner. The conical shape of the box and the central diaphragm serve to protect the pin-hole jet from becoming extinguished except when the gas is wholly 35 turned off by the usual gas-cock.

A represents a gas-burner constructed in the ordinary manner, except that it has a small aperture or pin-hole, *B*, in its lower part, through which a small stream of gas escapes 40 continuously while the gas is turned on.

C is a small cylindrical box, nearly closed at top and bottom. In the bottom of the box *C*, a little at one side of its center, is an opening, *D*, of such a size as to receive and fit upon 45 the base of the burner *A*, which supports the attachment *C*. Near the center of the top of the box is a diaphragm, *C'*, having a circular

opening, *E*, provided with an upwardly-projecting collar or flange, *F*. The opening *E* is made larger than the burner *A*, to permit the 50 passage of gas and air as well as the burner. The box *C* is provided with a conical top, *G*, in the apex of which is an opening a little larger than the gas-burner. When the article is in use the top of the cap *G* stands a little below 55 the tip of the burner *A*, as shown in Fig. 1.

With this construction, when the gas is turned on and lighted, the small stream of gas escaping from the pin-hole *B* will take fire and will burn within the box *C*; and should the 60 flame at the tip of the burner *A* be blown out, through ignorance or thoughtlessness, or by accident, the escaping gas will be at once ignited from the small flame at the pin-hole *B*, so that it will be impossible for the gas-burner 65 light to be permanently extinguished while the gas is turned on. The peculiar construction of this attachment prevents the flame at the pin-hole *B* from being extinguished by air-currents entering the opening in the upper end of the 70 cap *G*, as the entering blast of air will be distributed around the walls of the cap *G*, and will not pass through the opening *E* in the diaphragm *C'* with sufficient force to extinguish the flame at the pin-hole *B*. 75

Having thus described my invention, I claim as new and desire to secure by Letters Patent—

1. An anti-extinguisher attachment for gas-burners, made substantially as herein shown 80 and described, consisting of a conically-topped box, with central diaphragm and openings to admit the body of the burner and the passage of gas, as set forth.

2. In an anti-extinguishing attachment for 85 gas-burners, the combination, with the burner *A*, provided with an escape-orifice, *B*, of the conically-topped box and its central diaphragm provided with openings, as herein shown and described.

GEORGE E. SMITH.
